UNITED STATES PATENT OFFICE.

DAVID W. KLAU, OF NEW YORK, N. Y.

DUPLEX SEWING MACHINE.

Application filed December 5, 1925. Serial No. 73,311.

This invention relates to duplex sewing machines for making two parallel lines of stitching simultaneously, particularly for sewing at one time the two side hems of a strip of roller-shade material. The object of the invention is to provide certain improved features for facilitating the adjustment of the machine and the doing of the work.

10 In the accompanying drawings forming a part hereof:

Fig. 1 is a front elevation of a machine embodying the features of the invention;

15 Fig. 2 is a plan view showing the material, an intermediate portion of the strip being hemmed being broken out in order to show the parts of the machine beneath;

Fig. 3 is a vertical section, on a larger scale, taken on the line 3—3 of Fig. 2;

20 Fig. 4 is a vertical section taken on the line 4—4 of Fig. 2, looking from the rear, as indicated by the arrows, a portion of the framework at one end being broken out to show a rack;

25 Fig. 5 is a fragmentary vertical sectional elevation on an enlarged scale, taken in the same plane as Fig. 4 but looking from the front at one of the thread-holding and cutting devices;

30 Fig. 6 is a section taken at right angles to Fig. 5, showing the same parts;

Fig. 7 is a section taken on the line 7—7 of Fig. 5, showing the thread-holder and cutter in actuated position; and

35 Fig. 8 is a fragmentary front elevation showing a bracket secured to the bottom of the right-hand machine of Fig. 1.

The machine has a flat-top table or support 2, supported on suitable uprights 3. The table is constructed so as to have a wide transverse slot 4 forming an opening through the top. This slot or opening is advantageously formed between transverse beam members 5. In the upper inner edges 40 of these table members are rabbeted ways 6, on which the bases 7 and 7^a of two sewing machines 8 and 8^a are supported. Said machines are laterally spaced toward opposite ends of the slot 4 of the table, and are reversed so that the heads 9, 9^a of the machines are opposed to each other.

The two sewing machines are driven in unison from transverse shafts 10 and 10^a mounted in suitable bearings 11 and 11^a in 45 the under part of the table beneath the slot 4. The two shafts lie beneath the respective

machines and are geared together so as to rotate in opposite directions by meshing gears 12 on their proximate ends. The drive from the opposite revolving shafts to the 60 sewing machines consists of sprocket wheels 13 and 13^a on the shafts, with sprocket chains 14, 14^a passing over these wheels and over other sprocket wheels 15, 15^a on the sewing machines, the chains passing through the 65 slotted opening 4.

One or both of the sewing machines are relatively movable to vary the spacing between them. In the accompanying drawings the machine 8 is ordinarily a stationary machine, but may have its position changed if desired by shifting it on the ways 6. In that event the set-screws securing the wheel 13^a to the shaft 10^a are loosened, so that the wheel may be properly positioned beneath the sprocket wheel 15^a. 70

75 The machine 8 is shiftable as a matter of regular use of the machine, so that the two machines will apply the lines of hem-stitching in proper relation to the hems of all shade strips regardless of variations in width. The base 7 of this machine is freely 80 slideable on the ways 6, and special mechanism is provided enabling the operator sitting at the front of the tab'e to adjust the position of the machine quickly and accurately without leaving her place. A bracket 16, screwed to the under side of the base 7 and extending downward therefrom, is formed at its lower end as a shifter-fork 17 85 engaged a grooved collar 18 of the sprocket wheel 13, and this sprocket wheel is freely 90 slideable along the shaft 10, which is formed with a longitudinal groove 19 engaged by 95 a key 20 in the sprocket wheel.

The bracket 16 is also made with a bearing 21, through which passes a shaft 22. This shaft is disposed at right angles to the ways 6, and extends forward beneath the table to the front, where it is provided with a hand-wheel 23 for rotating it. The shaft travels with the machine 8 when the latter is shifted, and the beam members 5 are longitudinally slotted at 24 to permit the passage of the shaft and its translational movement. These beams are recessed along their outer faces adjoining the slots, and in the upper portions of these recesses are fixed longitudinal racks 25 with their teeth on their under side. Two pinions 26 fixed on the 100 shaft at these points mesh with the teeth of the racks, so that rotation of the shaft will 105

drive the sewing machine along the ways in one direction or the other, depending upon the direction in which the hand-wheel is turned. The location of the pinions at opposite sides of the bearing 21 insures an even application of pressure to shift the sewing machine.

Means are also associated with the shaft 22 and hand-wheel 23 to enable the sewing machine 8 to be clamped or locked at its various positions. A collar 27 fixed to the shaft at the inner side of the front beam 5 and provided with a washer 28 constitutes one clamp element adapted to be forced against this clamping abutment face. The hand-wheel 23 is connected to the outer end of the shaft in a manner indicated at 29 so as to permit it to have slight longitudinal movement thereon, and this movability is utilized to apply clamping pressure through a spacer tube 30 to the abutment face of a slotted cover plate 31 which is applied to the outer side of said beam, covering the recess therein. A wing-nut 32 engages screw-threads 33 on the outer end of the shaft, and constitutes an embodiment of an actuating device adjacent the hand-wheel to react between the concentric members so as to draw outward on the inner part and press inward on the outer part, thus applying the clamping elements to the abutment faces. A turn of the nut 32 in the unscrewing direction releases the lock, whereupon turning of the hand-wheel shifts the sewing machine 8. The precise positioning of the machine is thereby quickly and easily obtained, and the operator then tightens the nut 32 to lock the position.

The mechanism for driving the two sewing machines which has been described has the advantage of simplicity, and permits two ordinary sewing machines to be used, with an inexpensive change in one of them to reverse its feed, so that in the reversed position of the machine it will feed in the same direction as the other machine. The positive drive compels the two machines to operate in exact unison; and they can be disconnected from each other for re-threading and re-timed very readily by tilting the machine 8^a so as to free the sprocket chain 14^a. Before re-applying the chain, the sprocket wheel 15^a of this sewing machine is turned to the proper point so that when the chain is put on again the two machines will be in the same phase.

The strips of shade fabric come to the operator rolled up and with their side hems folded but not sewed. Heretofore it has been customary for the operator to hold the roll in her lap while she unrolls and sews it. A feature of the present invention is the provision of an adjustable roll-holder on the front of the table. This holder preferably comprises two curved metal straps 34, 34^a

projecting from the front of the table. One of these members, that marked 34^a, may be fixed, its rearward extension 35 being screwed to the under side of the table. The other member 34 is made shiftable with the sewing machine 8, so that the holder will be adjusted to the length of roll. For this purpose, the holder member 34 is carried by, or formed with, a long, variously bent bracket 36, which is screwed to the under side of the base 7 of the sewing machine 8, thence extending forward in a circuitous manner to avoid parts beneath the table, and at the front of the table being curved to form the member 34. Consequently, when the machine 8 is shifted to vary the spacing between the two machines, the roll-holder is likewise automatically adjusted.

The adjustable holder member 34 is braced by a supporting bar 70, which extends transversely beneath the forward portion of the bracket, the ends of this bar being secured to the under side of the table. The bracket rests upon this support and slides along the same when the holder member 34 is shifted to right or left.

Still another feature of the invention relates to thread-cutting and holding devices, which materially simplify the duties of the operator of this duplex machine; and means are provided whereby these devices are relatively adjustable with the adjustment between the sewing machines.

In the particular construction illustrated, the table is formed with a narrow slot 37 parallel with and behind the slot opening 4. In this slot are fixed metal bars 38, 39 separated by a thin slot 40. In this way, a slotted guide is formed, and the upper front corner edge of the guide slot constitutes a stationary shear element.

The movable thread-holding and cutting devices are marked 41, 41^a, and since they are or may be of duplicate construction, the same reference characters will be applied to the parts of both. Each device has a standard consisting of a plate 42 which has a sliding fit in the guide slot 40. On the upper part of this standard are a laterally overhanging cutting blade 43 and yielding presser-foot 44. The blade 43 is advantageously formed integral with the plate 42 and in the same plane therewith, so as to enter the slot 40 and coact with the stationary cutting edge at the front thereof. The presser-foot 44 lies in front of the blade 43, has a friction pad 45 on its under side, and is vertically movable relatively to the plate and blade. For this purpose a horizontal flange 46 is provided on the plate at the top of the blade projection, this flange being perforated with holes to receive headed studs 47, which project upward from the presser-foot. Coil springs 48 about these studs exert pressure between the presser-

foot and the flange 46 so as to hold the presser-foot thrust downward relatively to the plate and knife. When the blade enters the slot to cut the thread, the presser-
5 foot bears under spring-pressure upon the top of the table, gripping the thread.

The lower portions of the plates 42, below the guide slot 40, are connected, or in operative relation, to suitable operating
10 means. An advantageous embodiment of such means is one including a transverse, vertically movable rod 49, on remote portions of which the lower ends of both the plates 42 are mounted, the said ends being
15 formed with collars or bearings 50 for the purpose. At an intermediate point the horizontal rod has connected to it the upper end of a pull connection 51 extending downward to a pedal 52. The rod has slabbed portions
20 53 at suitable points, which are guided in guides 54 projecting downward beneath the table. The upward and downward movements of the rod are limited by stops 55,
25 56, and springs 57, 58, 59 disposed at appropriate points serve to hold the rod in its upper position, with the thread-cutters and holders raised above the table top.

The plate 42 of the device 41, which lies behind the head of the sewing machine 8, is shiftable along the rod 49, and lengthwise of the slot 40. This movement is effected in a very simple and direct manner by a finger 60 which is screwed to the top of the base of the sewing machine 8 and projects rearward therefrom into a vertical slot in the plate 42. In this way, the thread-holder and cutter is connected with the shiftable machine, so as to be shifted equally therewith, yet said device remains at all times in operative relation to its operating means, as the rod 49, and it is at all times free for up and down movement notwithstanding its shifter connection with the frame of the sewing-machine.

45 Another pedal 61 has a connection 62 extending upward to a control-box 63 for starting and stopping the sewing machines. The shaft 10^a is driven from this box by a belt 64 passing over pulleys. The source of power, preferably an electric motor, does not require illustration.

50 The slot opening 4 between the machines 8 and 8^a is closed, or approximately closed, by a suitable number of removable plates 65 with which the operator is provided, the plates resting on the guides 6.

55 What is claimed as new is:

60 1. In a machine of the character described, a table having ways, a sewing machine slidably mounted thereon, said table having an under portion providing clamp abutment faces extending parallel with said ways, mechanism for shifting the sewing machine along the ways having an operating shaft journaled in a bearing carried by

the sewing machine, said shaft extending at right angles to said ways and abutment faces and provided with a hand-wheel, clamping means on the shaft comprising two portions adapted to be forced in opposite directions to apply clamping pressure against said abutment faces, and an actuating device on the forward end of said shaft adjacent the hand-wheel to react between said portions of the clamping means. 70

2. In a double-hemming machine, the combination with a table, and two laterally spaced sewing machines mounted on said table so as to be relatively movable toward and from each other, of a roll-holder at the front of the table, said roll-holder comprising two relatively movable portions, and means whereby said portions are relatively shifted automatically with the relative movement between the sewing machines. 75

3. In a double-hemming machine, the combination with a table, and two sewing machines mounted in laterally spaced relation thereon, one of said machines being movable on ways to vary the spacing between the machines, of a roll-holder at the front of the table comprising two relatively movable members, and a bracket arm secured to and movable with said movable sewing machine and extending forwardly beneath the table and carrying one of the roll-holder members. 80

4. In a double-hemming machine, the combination with a table, and two sewing machines mounted in laterally spaced relation thereon, one of said machines being movable on ways to vary the spacing between the machines, of a roll-holder at the front of the table comprising two relatively movable members, and a bracket arm secured to and movable with said movable sewing machine and extending forwardly beneath the table and carrying one of the roll-holder members, and a transverse support on the table for the forward part of said bracket arm. 85

5. In a double-hemming machine, the combination with a table, and two laterally spaced sewing machines mounted on said table so as to be relatively movable toward and from each other, of a pair of thread-holding and cutting devices over the table behind said sewing machines, with joint operating means beneath the table for depressing said devices to hold and cut the threads, said table containing means to cooperate with said devices, and means whereby said devices are relatively shifted automatically with the relative movement between the sewing machines. 110

6. The combination with a table, and a sewing machine shiftable laterally thereon, of a thread-holding and cutting device likewise movable over the table back of the sewing-machine, the table being adapted to cooperate therewith, means beneath the table for operating said device, a connection be- 115
120
125
130

tween said device and the frame of said sewing machine for effecting shifting of said device always in operative relation to its operating means.

5 7. The combination with a table, and a sewing machine shiftable laterally thereon, of a thread-holding and cutting device over the table back of said sewing machine, said device being supported independently of 10 said sewing machine and being similarly shiftable, means in the table to cooperate with said device, means beneath the table for depressing the device, and a finger projecting from the base of the sewing machine to 15 shift said device.

8. The combination with a table, and a sewing machine shiftable laterally thereon, of a thread-holding and cutting device over the table back of said sewing machine, said 20 device being supported independently of said sewing machine and being similarly shiftable, means beneath the table for operating said device, and a connection from the frame of said sewing machine for shifting said 25 device.

9. In a double-hemming machine comprising a table and two laterally spaced sewing machines, one of said sewing machines being 30 movable laterally to vary the spacing between the machines, a pair of thread-holding and cutting devices behind said machines, a transverse vertically movable rod and means for operating the same to actuate both 35 said devices, and a connection whereby one of said devices is shifted along said rod with the shifting of the corresponding sewing machine.

10. The combination with a support, and a sewing machine shiftable thereon, of a 40 thread-holding and cutting device behind said machine, a horizontal vertically movable rod along which said device is shiftable, and means for depressing said rod.

11. The combination with a support and 45 a sewing machine shiftable thereon, of a thread-holding and cutting device behind said machine, a horizontal vertically movable

rod along which said device is shiftable, a slotted guide in the table wherein said device is operated vertically and is shiftable 50 horizontally, and means for operating the rod.

12. The combination with a support and a sewing machine shiftable thereon, of a thread-holding and cutting device behind 55 said machine, a horizontal vertically movable rod along which said device is shiftable, a horizontally extended guide and cutting edge, and means for operating said rod.

13. In a double-hemming machine comprising a table and two laterally spaced 60 sewing-machines thereon, a slotted guide in the table behind said sewing-machines, a pair of standards passing vertically through said 65 guide, cutting blades and presser-feet carried in laterally and inwardly overhanging relation by said standards, and pedal-operated means connected with the lower parts of both standards for depressing the same.

14. In a double-hemming machine comprising a table and two laterally spaced 70 sewing-machines thereon, a slotted guide in the table behind said sewing-machines, a pair of standards passing vertically through said 75 guide, cutting blades and presser-feet carried in laterally and inwardly overhanging relation by said standards, a transverse rod beneath the table to which the lower portions of both standards are connected, means for depressing said rod, and means for normally holding said rod and standards in the 80 upper position.

15. In a double-hemming machine comprising a table and two laterally spaced 85 sewing-machines thereon, a slotted guide in the table behind said sewing-machines, a pair of standards passing vertically through said 90 guide, cutting blades and presser-feet carried in laterally and inwardly overhanging relation by said standards, and a transverse vertically movable operating rod to which the lower portions of both said standards are operatively related.

DAVID W. KLAU.
